(57) **CLAIM**

The ornamental design for a hair brush sanitizing unit, as shown and described.

DESCRIPTION

FIG. 1 is a front perspective view of the first embodiment of the present invention, showing a sliding door open;
FIG. 2 is a front perspective view of the first embodiment of the present invention, showing the sliding door closed;

FIG. 3 is a bottom rear perspective view of the first embodiment of the present invention;

FIG. 4 is a rear side perspective view of the first embodiment of the present invention, showing the sliding door closed;

FIG. 5 is a front view of the first embodiment of the present invention, showing the sliding door open;

FIG. 6 is a rear view of the first embodiment of the present invention;

FIG. 7 is a right side view of the first embodiment of the present invention;

FIG. 8 is a left side view of the first embodiment of the present invention;

FIG. 9 is a top view of the first embodiment of the present invention, showing the sliding door closed;

FIG. 10 is a top view of the first embodiment of the present invention, showing the sliding door open;

FIG. 11 is a front perspective view of a second embodiment of the present invention, showing the sliding door open;

FIG. 12 is a front perspective view of the second embodiment of the present invention, showing the sliding door closed;

FIG. 13 is a bottom rear perspective view of the second embodiment of the present invention;

FIG. 14 is a rear side perspective view of the second embodiment of the present invention, showing the sliding door closed;

FIG. 15 is a front view of the second embodiment of the present invention, showing the sliding door open;

FIG. 16 is a rear view of the second embodiment of the present invention;

FIG. 17 is a right side view of the second embodiment of the present invention;

FIG. 18 is a left side view of the second embodiment of the present invention;

FIG. 19 is a reduced top view of the second embodiment of the present invention, showing the sliding door closed; and,
FIG. 20 is a reduced top view of the second embodiment of the present invention, showing the sliding door open.

The broken lines are illustrative of environmental structure only and form no part of the claimed design.
